COMBINED RECORD PLAYER AND CARRYING CASE FOR A PICTURE PROJECTOR

Charles R. Grover, Denver, Colo., assignor to The Sales
Master Corp., Denver, Colo., a corporation of Colorado

Application November 30, 1956, Serial No. 44,010

Term of patent 7 years

(Cl. D56—4)

The drawing is a front perspective view of a combined record player and carrying case for a picture projector, showing my new design.

The dominant feature of the design resides in the portions shown in full line in the accompanying drawing.

I claim:

The ornamental design for a combined record player and carrying case for a picture projector, as shown and described.
